OIL BURNER CONTROL

Vaughn H. Hardy, Rochester, N. Y., assignor to
 General Motors Corporation, Detroit, Mich., a
 corporation of Delaware

Application April 14, 1938, Serial No. 202,025

8 Claims. (Cl. 158—28)

This invention relates to control systems and more specifically to a control system for a source of heat, namely an oil burner or fluid heat furnace.

5 With the advent of the domestic use of fluid fuel burners such as oil or gas fire furnaces, it has become necessary to provide suitable controls for said burners or furnaces which will require very little, if any, attention, maintain the heat 10 at a predetermined set level, and embody certain safety features which will keep the device sufficiently safe for home use.

It is therefore an object of my invention to provide such a system for burner control.

15 It is a further object to provide a control system embodying the necessary safety features to deenergize the whole system under certain circumstances, namely, when the burner does not initially start or where there is a flame or current failure after the burner is operating normally.

20 It is a still further object of my invention to provide such a control system as will be comparatively simple in construction and easily applied to an existing heating plant.

25 With these and other objects in view, the embodiments of my invention will be best understood by reference to the following specification and claims and the illustrations in the accompanying drawings, in which:

30 Figure 1 is a circuit diagram of a control system of my invention.

Figure 2 is also a circuit diagram of a modified form of my invention.

35 Figure 3 is a circuit diagram of a further modification.

40 Referring now more specifically to Figure 1, there is provided an incoming line 2, 4 to which the supply such as 110 volts is provided. There is also shown the burner motor 6; the conventional form of stack switch 8, which has a bimetal portion 10 extending into and sensitive to the heat in the furnace chamber; a room thermostat 12; and a transformer relay 14 having a primary 16 and a secondary 18, the magnetic field of which operates a plurality of switches 20 and 22.

45 There is also provided an ignition transformer 24, the main warp switch 26 which includes a heating coil 28 and a switch 30, and a second warp switch or electrically heated time element 32 including a heating coil 34 and a plurality of switches 36 and 38 operated thereby. There is in the secondary circuit of the transformer relay 14 a resistance coil 40, the purpose of which will 50 become obvious.

The main warp switch 30 is connected directly to the line 4 and the opposite side is connected to its own heating element 28, the opposite side of the heating element being connected by line 42 to the primary 16 of the transformer relay 14. 5 The opposite side of the primary 16 is connected by a line 44 back to the incoming line 2. Line 4 is also connected directly to switch 22, the opposite side of which is connected by line 46 to the burner motor 6 which is also connected to the line 2 by a further line 48. Also connected to line 46 is a branch 50 which is connected both to the heating element 34 and one switch 36 of the group operated by the warp switch designated at 32. The opposite side of the heating coil 34 is connected back through line 52 to incoming line 2 and the opposite side of the switch 36 is directly connected to the primary of the ignition transformer 24 which is then directly connected to line 2. The secondary of the ignition transformer of course is connected to a pair of spaced contacts which provide sparks for ignition purposes. This concludes the high voltage side of the system and the secondary or low voltage side will next be described. 15

20 One terminal of the transformer relay secondary 18 is connected through line 54 to one side of the room thermostat 12 which has its opposite side connected to a switch 56 controlled by the stack switch and normally closed when cold. 25 Also in branch circuit to one terminal of the resistance 40 also connected to switch 56 is a line 58 which is connected to one side of the switch 38, the opposite side being directly connected to one terminal of the secondary 18 by line 60. 30

There is also a line 55 between line 58 and the opposite end of the resistance 40. A line 62 connects the opposite terminal of the resistance 40 to one of the switches 20 operated by the transformer relay which is then extended up to the 35 same terminal of the secondary 18 as that to which line 60 is attached. 40

The warp switch 30 is normally closed under all conditions and is only opened when some abnormal safety condition requires it to do so. The room thermostat is of course opened when the temperature of the room is above a certain predetermined level and closed as the temperature falls below that level. The stack switch 8 is closed when cold and opens upon an application of heat. The warp switch 32 is cool when the system is deenergized and switches 36 and 38 are closed but the heating element 34 is heated for the whole period that the motor 6 is in oper- 45 50 55

ation and the switches 36 and 38 open as the heat of element 34 is applied thereto.

It will be noted therefore that the primary 16 of the transformer relay is always energized under normal conditions. Therefore if the room thermostat 12 closes its contacts to call for heat, the following circuit will be completed: 12, stack switch 56 (closed when cold), 58, 38 (closed when cold), 60, secondary 18 and line 54. This causes considerable current to be drawn by the transformer and the magnetic field of the same will increase appreciably which causes a closing of the two switches 20 and 22. The closing of switch 22 closes an obvious circuit to the burner motor 6 and at the same time a parallel circuit through the heating coil 34, the ignition transformer 24 and switch 36.

Under these conditions the burner motor will of course start to discharge a combustible mixture into the chamber and the ignition will be present to ignite this mixture. The heating element 34 however will tend to cause the switch 36 to open after a predetermined interval which cuts off the ignition and the burner thereafter continues to function normally. The closure of switch 20 closes a shunt circuit around the warp switch 38. This however acts to complete the secondary when 38 opens due to the heat of the warp switch which will be actuated at the same time that switch 36 opens due to the heat of the element 34. When the stack switch 56 however opens, due to burner temperature rise, then the amount of current drawn by the secondary 18 will decrease to a comparatively low value with just enough being drawn to maintain the switches 20 and 22 closed but insufficient to cause the heating element 28 to open its bimetallic switch 30. This is due to the inclusion of the resistance 40 in series in the secondary. The burner will therefore continue to operate until a sufficient amount of heat has been provided and when the room thermostat opens the whole system will return to its normal deenergized condition.

If, for example, for some reason the flame does not ignite when the motor starts, the switch 56 will remain closed and the secondary of the transformer relay will continue to absorb a comparatively large amount of current which will of course necessitate a comparatively heavy current flow through the primary 16 and the heating coil 28 which will, after a predetermined time, cause the safety switch 30 to open and the whole system will then be deenergized. The safety switch 30, as in most conventional switches of this type, requires a manual resetting after it is once opened. Likewise, if the burner has been operating normally and for some reason the flame is extinguished momentarily, the stack temperature will begin to descend and switch 56 will close which will, as before, require a heavy current flow through the secondary and therefore the primary of the transformer 14 and the heating coil 28 of warp switch 26 will again cause safety switch 30 to open. If, during normal operation, the current is caused to cease for a short period of time, the switches 20 and 22 will open. At such time, however, the stack switch 56, as well as switch 38, is open, and if the current returns immediately the secondary circuit cannot be closed until both these two switches close upon cooling of the stack switch and warp switch which requires a short period of time which is utilized for purging the furnace of any excessive fumes and allows it to cool down to some extent before the burner motor can again be energized

to throw oil or the combustible mixture into the furnace. Under these conditions, the switch 38 is provided to be operated jointly with the ignition switch 36 to positively prevent starting of the burner without ignition such as might occur, for instance, if such switch 38 were not provided and the stack switch 56 returned to its cold closed position prior to closing of the ignition switch 36 by cooling of the heating coil 34.

The system shown in Figure 2 is a modification of that shown in Figure 1. In this instance the transformer relay 14 is connected to the main warp switch 26 in exactly the same way and it operates its two switches 20 and 22 in the same manner as before. The warp switch 32 is however altered as shown at 32' and a heating coil 64 operates a switch 68 which controls the ignition transformer 24. The resistance 40 still shunts the switch 56 operated by the stack switch 8. The main difference is that the warp switch 32 has in this instance only one contact, namely that for operating the ignition transformer and does not control the circuit through the stack switch which is in shunt with the control resistance 40. The normal operation of this circuit is substantially the same as shown in Figure 1 for upon closure of the room thermostat 12 the secondary 18 of the transformer relay is energized which draws current from the primary and causes the closure of the two switches 20 and 22, 30 the first completing the circuit through the shunt resistance 40 and the second completing the circuit for the second warp switch, the ignition and motor.

As before, when the stack switch opens the current through the secondary 18 is cut down due to the series relation of the resistance 40, but there is sufficient magnetic force to maintain the switches 20 and 22 closed. When a sufficient amount of heat has been provided the room thermostat opens to deenergize the whole system. As far as the safety features are concerned, this system operates substantially the same as that shown in Figure 1, with the exception that since there is no switch in series with the stack switch and operated jointly with the ignition switch, as provided in Figure 1 by switch 38, it is necessary to so construct the warp switch 32' for the ignition switch 68 that in the event of a momentary current failure such ignition switch will be closed by cooling of the heating coil 64 before the stack switch 56 closes on cooling of the stack to prevent starting of the burner motor without ignition.

The system disclosed in Figure 3 has a slightly different variation in that in this case the second warp switch 32 of Figure 1 or 32' of Figure 2 is eliminated entirely and the warp switch 26' in this instance is provided with an extra switch 68 which controls the ignition transformer 24. The circuit is otherwise the same as that shown in Figure 2. It should be pointed out however that in this construction it is necessary to design the two switches 30 and 68 in such a manner that they will operate at different times; in other words, a certain amount of heat is necessary to operate ignition switch 68 to open position but at this time safety switch 30 will still remain closed and it will require a substantial increase in the amount of heat supplied before the switch 30 will open so that under normal running conditions of the burner the ignition switch 68 will be opened soon after starting the burner and the safety switch 30 remain closed. This can be done of course by merely designing the bimetal switch 75

actuating element so that this result can be obtained.

The operation in this case is exactly the same whereby the closure of room thermostat 12 will, 5 through the closed stack switch 56, complete the secondary circuit of the transformer relay 14 which will then cause the two switches 20 and 22 to close and the motor 6 and ignition transformer 24 will be energized through the closed 10 switches 38 and 68. After a predetermined time, switch 68 will open cutting off the ignition, but as before mentioned safety switch 30 is so designed as to remain closed for a longer period and before this time has elapsed switch 56 should 15 open due to actuation of the stack switch 8. However the amount of current drawn by the secondary after 56 opens because of the resistance 40 is enough to maintain a sufficient amount of heat by coil 28 in the primary to keep the 20 switch 68 open as long as the burner operates. In this case of course if the burner does not ignite, safety switch 30 will eventually open de-energizing the whole system, or if the flame is 25 extinguished for any reason switch 56 will close after a short interval due to the cooling down 30 of the stack and this will again cause switch 30 to open. If the current fails, contacts 20 and 22 will open and the secondary cannot again be energized until the switch 56 is closed by cooling 35 of the stack which will allow a purging time for the furnace.

I claim:

1. In a system for controlling fluid fuel burners, a burner circuit, an electrically heated safety switch controlling said burner circuit, a heating element for said switch in series therewith, a transformer having its primary in series therewith, a secondary circuit for the transformer and means in the secondary circuit and actuated by 40 temperature changes of the burner to vary the flow of current therethrough which causes a variation of current flow in the primary and said heating element to control the actuation of the safety switch thereby.
- 45 2. In a control system for fluid fuel burners, a burner circuit, an electrically heated safety switch controlling said burner circuit, a heating element for said switch in series therewith, normally maintained energized at all times, a transformer primary winding in series therewith and with a source of power, a secondary transformer winding in inductive relationship to the first, a resistance in series with the secondary circuit, a shunt circuit around the resistance and means 50 actuated by temperature changes of the burner to apply or remove the shunt thereby varying the current in the secondary which reflects back into the primary and affects the operation of the safety switch by said heating element.
- 55 3. In a control system for fluid fuel burners, a motor for discharging combustible mixture into the burner, a switch for controlling motor operation, a transformer having windings located in juxtaposition to the switch so that the magnetic field will operate the same, an electrically heated safety switch in series with one of the windings, a heating element for said safety switch in series therewith, a resistance in series with the other winding and means actuated by temperature 60 changes in the burner to shunt the resistance whereby the flow of current may be varied in that winding which reflects a change in flow in the other winding and in the operation of the safety switch by said heating element.
- 70 4. In a control system for fluid fuel burners, a

burner circuit, a transformer, a warp switch and a heating element for said switch in series with the transformer primary and normally having the transformer no-load current flowing there-through at all times, said switch controlling the 5 burner circuit, a transformer secondary, a thermostat and a stack operated switch in series with the secondary to cause a high current to flow, and a resistance in shunt to the stack switch and limiting the secondary current when the stack 10 switch opens.

5. In a control system for fluid fuel burners, a source of current, a transformer relay having a primary and secondary winding, the primary winding being connected to the source, an electrically heated warp switch and a heating element for said switch connected in series with the primary and normally in circuit at all times, a burner circuit controlled by said warp switch, a thermostat, a resistance, both in series with 20 the secondary winding, a shunt circuit around the resistance, switching means in the shunt circuit and means responsive to temperature changes of the burner connected to and operating the switching means whereby burner temperatures 25 will alter the secondary current and reflect through the transformer to vary the primary current and operate the warp switch.

6. In a control system for fluid fuel burners, a source of current, a transformer relay having 30 a primary and secondary winding, the primary winding being connected to the source, an electrically heated warp switch and a heating element for said switch connected in series with the primary and normally in circuit at all times, a 35 thermostat, a resistance, both in series with the secondary winding, a shunt circuit around the resistance, switching means in the shunt circuit, means responsive to temperature changes of the burner connected to and operating the switching 40 means whereby burner temperatures will alter the secondary current and reflect through the transformer to vary the primary current and operate the warp switch, a motor for discharging fuel into the burner and switching means 45 for the motor operated by the transformer relay whereby as the current is reduced when the resistance is included in the secondary the flux of the transformer will maintain the motor switch closed but will be unable to close it.

7. In a system for controlling fluid fuel burners, a burner motor circuit, an ignition circuit, an electrically heated safety switch controlling said circuits, a heating element for said switch in series therewith, a transformer having its primary in series with said switch and heating element, a secondary circuit for the transformer, means in the secondary circuit actuated by temperature changes of the burner to vary the flow of current in the secondary circuit to cause a 60 variation of current flow in the primary and thereby control the actuation of said safety switch by said heating element, a burner motor switch in said motor circuit, means including a thermostat in the secondary circuit to control 65 said motor switch, an ignition switch in said ignition circuit, a thermal time element for operating said ignition switch, and a switch in the secondary in series with said thermostat and operated by said thermal time element to prevent closure of the burner motor circuit unless the ignition circuit is also closed.

8. In a system for controlling fluid fuel burners, a transformer relay having primary and secondary windings, a burner motor circuit, an ig- 70

75

75

nition circuit, an electrically heated safety switch controlling said circuits, a heating element for said safety switch in series therewith and in series with the primary winding, a thermostat and 5 a resistance in series with the secondary winding, a shunt circuit around the resistance, a switch in said shunt circuit, means responsive to burner temperature connected to and operating said switch, a relay switch in said burner circuit, 10 means including said thermostat for controlling

said relay switch, a thermal time element controlled by said relay switch, a normally closed ignition switch in said ignition circuit operated by said thermal time element, and a switch in the secondary in series with said thermostat and secondary winding, said switch being also operated by said thermal time element to thereby prevent closure of said relay switch unless the ignition circuit is closed by said ignition switch. 5

VAUGHN H. HARDY. 10
